BOILER CLEANER

Frank Bowers, Detroit, Mich., assignor to
 Diamond Power Specialty Corporation, Detroit,
 Mich., a corporation of Michigan

Application May 5, 1924, Serial No. 711,275
 Renewed March 23, 1933

19 Claims. (Cl. 122—392)

This invention relates to boiler cleaners and has for its object the provision of a new and improved apparatus for cleaning soot or the like from boiler or other heat exchanger parts.

5 In the drawings:—

Figure 1 is a view in side elevation of a unitary head providing a journal bearing for a blower element, a steam passage to said element, a valve controlling said passage and 10 mounting a common mechanism for actuating said blower and controlling said valve;

Figure 2 is a sectional view of the same taken on the line 2—2 of Fig. 1;

15 Figure 3 is a sectional elevation of the valve and certain means associated therewith to facilitate opening of said valve and to regulably retard its closing;

Figure 4 is a view of the same with the valve open.

20 In these views the reference character 1 designates a blower element for the discharge of a cleaning fluid. The inlet end of said element is journaled in a bearing 2 carried by the upper end of a gooseneck passage 3 for the cleansing 25 fluid, which passage is adapted to discharge through said bearing into the blower element. The flow through said passage is controlled by a valve 4 mounted within a casing 5 carried by the lower end of the gooseneck member 3. The 30 parts 2, 3 and 5 are preferably integral, forming a unitary head. 6 is a port within the casing 5 controlled by the valve 4, and 6^a is a supply pipe for the cleaning fluid connected to the lower end of said casing. It is to be noted 35 that said valve seats under pressure of the fluid delivered to said pipe.

The sleeve 8, formed preferably integral with the valve 4, extends centrally from the upper side thereof through the port 6 and through the 40 passage 7 within the gooseneck member. Fast upon the upper end of said sleeve is a piston 9 which is reciprocatory within a cylindrical chamber 10 formed in the upper portion of the casing 5. Said piston and said chamber have 45 their upper portions of an increased diameter, thus forming an annular shoulder 11 upon the piston and a corresponding shoulder 12 upon said chamber, said shoulders being engageable to limit downward travel of the piston. The 50 passage 12^a through the sleeve 8 opens at its lower end in the under face of the valve 4 and provides for a flow of the cleansing fluid from the high pressure side of said valve (that is to say, from below the valve) to the chamber 10 above the piston 9. Such flow is controlled by

a relatively small auxiliary valve 13 seating marginally on the lower end of the passage 12^a and carried by a stem 14 passing through said sleeve and fluted as indicated at 15 to permit steam to flow between said stem and sleeve. Said 60 stem passes through the chamber 10 and projects above the casing 5. The upper portion of said stem is slidable within a tubular stem 16 which is itself slidable in a packed bearing 17 carried by the upper end of the casing 5. Within 65 the piston 9 a sleeve valve 18 is mounted fast upon the lower end of the tubular stem 16, said valve engaging a cylindrical portion 19 of the interior wall of said piston. Passages 20 are extended through said valve parallel to its axis, 70 said passages providing for a free flow of the cleaning fluid to the upper portion of the chamber 10 when unseating of the auxiliary valve 13 allows said fluid to flow up through the 75 sleeve 8. Intermediate its ends, the sleeve valve 18 is formed with ports 21 in communication with the passages 20 and registering under certain 80 conditions with exhaust passages 22 extending through the wall of the piston 9 and opening into a chamber 23 formed by an annular channel in the exterior face of said piston. In its 85 lower portion said piston has formed a plurality of passages 24 through its wall which are adapted to communicate under certain conditions (see Figure 3) with an annular space 25 formed between the shoulders 11 and 12. In all positions of said piston the annular spaces 23 and 25 communicate with branches 26 and 26^a of an exhaust pipe 27. The flow through 90 the branch 26 is regulable by a valve 28.

Upon the upper end of the tubular stem 16 there is screw threaded a cap member 29 which is outwardly flanged as indicated at 29^a to form an abutment for the upper end of a coiled spring 30, the lower end of which seats upon the 95 casing 5. Normally said spring establishes the uppermost limiting position of the tubular stem 16 and sleeve valve 18 shown in Figure 3, this position being determined by engagement of said stem with a nut 31 screw threaded upon the upper end portion of the inner stem 14. A relatively weak spring 32, coiled around the stem 14 between an intermediate interior shoulder of the tubular stem 16 and said nut, normally 100 maintains the raised limiting position of the stem 14 shown in Figure 3 and the corresponding closed position of the auxiliary valve 13 likewise shown in said figure.

105 While the described valve mechanism may be 110

variously actuated, there is disclosed a preferred actuating means in common with which the blower element 1 is driven. Thus, a gear 33 fast upon said blower element is engaged by 5 a driving pinion 34 fast upon a shaft 35 mounted upon the head 2, 3, 5 above said blower element by arms 35a. Upon said shaft is also fast a driving chain wheel 36. To one side face of the gear 33 there is secured a cam 10 member 37 which, during a predetermined portion of the rotation of said gear, engages and depresses a pivotal trip lever 38 having its lower portion bearing upon the cap 29.

To compel an oscillatory actuation of the 15 blower element 1, suitable stop mechanism is provided limiting turning of said element in each direction. Thus, as is seen in Figures 1 and 2, a pair of stops 40 and 41 may be adjustably secured upon the periphery of the gear 33, 20 said stops engaging the pinion 34 upon a predetermined angular actuation of said gear. The arrangement disclosed is such as to permit a closing movement of the valve in one of the limiting positions of travel of the blower element. That is to say, when the stop member 25 41 engages the pinion 34, the cam 37 has previously passed out of engagement with the trip lever 38 so that the latter no longer acts to depress and open the valve 4.

30. In the operation of the described device, when the cam 37 forces the trip lever 38 angularly downward, said lever bearing upon the cap 29 initially depresses the tubular stem 16 and the sleeve valve 18, the exhaust passages 22 and 24 35 being closed by this travel of said valve. This initial movement of the cap 29 engages the same with the upper end of the valve stem 14, and the continued downward actuation of said cap moves the two stems 14 and 16 in unison, thus unseating the auxiliary valve 13. Immediately upon unseating of the auxiliary valve the cleaning fluid passes up through the sleeve 8 and through the openings 20 of the valve 18 and exerts a downward pressure upon the 40 upper face of the piston 9. Since the area of this piston exceeds that of the valve 4, the latter valve is now unseated by the fluid pressure on the piston, said piston moving down until the shoulders 11 and 12 engage as shown in 45 Figure 4, the corresponding open position of the valve 4 being likewise shown in said figure. The cleaning fluid is now delivered through the gooseneck member 3 and through the bearing 2 to the blower element. After actuation 50 of said element through a predetermined arc the stop 40 encounters the pinion 34, limiting rotation in that direction. The operator then reversely actuates the chain wheel 36, and the delivery of the cleaning fluid to the blower 55 continues until, through this reverse actuation of the parts, the cam 37 disengages the lever 38. Thereupon, the spring 30 acting on the cap 39 raises the tubular stem 16 and sleeve 60 valve 18 to their position shown in Figure 3, the stem 14 and valve 4 being at the same time raised to partially close said valve. Raising of the sleeve valve registers the ports 21 with the passages 22 while raising of the stem 65 20 effects a closing of the auxiliary valve 13. Steam above the piston 9 exhausts gradually through the passages 22, and since the area of these passages is small in comparison to the volume of steam contained in the chamber 10 70 above the piston, the upward movement of the 75

piston and the resultant closing of the valve is quite gradual.

When this gradual movement has proceeded sufficiently to raise one or more of the passages 24 sufficiently to place the same in communication with the space 25, a relatively quick discharge of the steam trapped above the piston 9 takes place. Thereafter, the closing movement of the valve 4 is quite rapid. The speed with which the valve 4 seats during its initial retardation is regulable by means of the valve 28, since the latter controls the escape of steam exhausting from the passages 22. The accelerated speed with which the final seating movement of the valve 4 occurs is regulable by adjusting the nut 31 up or down upon the stem 14, this adjustment acting to uncover the passages 24 to a greater or less degree, the speed of this final closing being proportionate to the total outlet area of said openings. The primary advantage 90 of the described retardation of the closing movement of the main valve 4 lies in the fact that when the controlled blower element is of an oscillatory type, in at least one limiting position of said blower, said valve is permitted a closing 95 movement. If this movement were not retarded, said valve would seat before the operator, through reverse actuation of the mechanism, could again engage the cam 37 with the lever 38. It would then be necessary to overcome 100 the fluid pressure and also the pressure of the spring 30 holding the valve to its seat. By retarding the initial seating movement of the valve as above described, the operator has ample 105 time to reversely actuate the control mechanism 110 sufficiently to again impose a depressing force upon the valve before the latter has completed its retarded travel.

If the entire seating movement of the valve were retarded there would be a continued discharge of steam from the blower element for a considerable time after discontinuance of operation of the same, and this continued fixed discharge would be injurious to the parts of the boiler encountered. Therefore, the invention 115 retards only an initial portion of the closing movement of the main valve sufficient to give the operator time to apply an opening force to the valve through a reversal of operation. Upon discontinuance of operation of the blower the 120 initial period of gradual seating movement is sufficiently short to prevent damage to the parts encountered by the fluid discharged from the blower element, during such period the final 125 closing movement being quite rapid.

130 For the sake of convenience the invention has been described as being incorporated in a device for cleaning boilers. It will be apparent, however, that the inventive principles disclosed may be incorporated in devices for cleaning apparatus similar to boilers, and it is to be therefore understood that the term "boiler" wherever used throughout the specification and claims is to be construed as meaning a fluid heater or heat transfer apparatus of any character, while the term "boiler cleaner" is to be construed as meaning a cleaner for any such type of apparatus.

135 What I claim as my invention is:—

1. In a boiler cleaner, the combination with a rotatable blower element and a fluid passage 145 leading thereto, of a valve controlling the same, means responsive to rotation of the blower element for unseating said valve, and means for retarding said valve during a portion only of its seating movement.

2. In a boiler cleaner, the combination with a rotatable blower element, a fluid passage leading thereto, and a valve controlling the same, of means responsive to rotation of the blower element for unseating said valve, said valve being adapted to close when not acted on by said means, and means for retarding said valve during the initial portion only of its closing movement. 80
3. In a boiler cleaner, the combination with a rotatable blower element, a fluid passage leading thereto, and a normally closed valve controlling the same, of means responsive to rotation of the blower element for unseating said valve and means for retarding said valve during the initial portion only of its seating movement, and means for varying the ratio of the retarded travel of the valve to its entire seating travel. 85
4. In a boiler cleaner, the combination with a rotatable blower element, a fluid passage leading thereto, and a normally closed valve controlling the same, of means responsive to rotation of the blower element for unseating said valve, means for retarding the seating travel of the valve during an initial portion only of such travel, and means for regulating the degree of such retardation. 90
5. In a boiler cleaner, the combination with a rotatable blower element, a fluid passage leading thereto, and a valve controlling the same and seating under pressure of the fluid in said passage, of means responsive to rotation of the blower element for unseating said valve, means for opposing pressure of the fluid controlled by the valve to retard seating travel of the valve, and means for rapidly relieving the retarding fluid pressure prior to seating of the valve. 95
6. In a boiler cleaner, the combination with a blower element and a valve controlling the delivery of a cleaning fluid to said element, of means responsive to a movement of the blower element for causing the cleaning fluid to move said valve to open position, and means for regulably retarding seating of said valve. 100
7. In a boiler cleaner having a blower element and a valve controlling the supply of cleaning fluid to said element, means for oscillating said blower element within predetermined limits, and means responsive to an initial rotative movement of said element from one of said limits toward the other for causing the pressure of the cleaning fluid to exert a force tending to unseat said valve, said means acting in one limiting position of the blower element to retard movement of the valve during the initial closing movement only. 105
8. In a boiler cleaner, the combination with a movable blower element, a passage for supplying cleaning fluid to said blower element, a valve controlling the flow of cleaning fluid through said passage and seating under the pressure of the fluid in said passage, and means for unseating said valve in timed relation to the movement of said blower element, of means for retarding said valve during an initial portion only of its closing movement. 110
9. In a boiler cleaner, the combination with a movable blower element, a passage for supplying cleaning fluid to said blower element, a valve seating under the pressure of the cleaning fluid for controlling the flow of cleaning fluid through said passage, and means for unseating said valve in timed relation to the movement of said blower element, of means for employing the pressure of the fluid to retard the initial seating movement only of said valve. 115
10. In a boiler cleaner, the combination with a movable blower element, a passage for supplying cleaning fluid to said blower element, a valve for controlling the flow of cleaning fluid through said passage, said valve seating under the pressure of the fluid in said passage, and means for unseating said valve in timed relation to the movement of said blower element, of a piston connected to said valve, a chamber in which said piston reciprocates, means for admitting said fluid to said chamber to act on said piston to retard seating of the valve, means for gradually venting said chamber during the initial seating travel of the valve, and means for rapidly venting said chamber during the final portion of such travel. 120
11. In a boiler cleaner, the combination with a rotatable blower element, a passage for supplying cleaning fluid to said blower element, a normally closed valve for controlling the flow of cleaning fluid through said passage, means for rotating said blower element, and means actuated by said blower element rotating means for opening said valve, of means for retarding said valve during an initial portion only of its closing movement. 125
12. In a boiler cleaner, the combination with a rotatable blower element, a passage for supplying cleaning fluid to said blower element, a normally closed valve for controlling the flow of cleaning fluid through said passage, means for rotating said blower element, and means actuated by said blower element rotating means for opening said valve, of means for utilizing the pressure of the cleaning fluid to retard the initial seating movement only of said valve. 130
13. In a boiler cleaner, the combination with a movable blower element and a valve controlling the delivery of a cleaning fluid to said blower element, of means responsive to a movement of the blower element for causing the cleaning fluid to exert a pressure on said valve to unseat the same, and means for retarding said valve during the initial portion only of its closing movement. 135
14. In a boiler cleaner, the combination with a movable blower element and a valve controlling the delivery of a cleaning fluid to said blower element, of means responsive to a movement of the blower element for causing the cleaning fluid to exert a pressure on said valve to unseat the same, and means providing for a retarded initial closing of said valve and a subsequent rapid closing thereof. 140
15. In a boiler cleaner having a blower element rotatable in opposite directions, and a valve controlling the supply of a cleaning fluid to said blower element, said valve normally being seated under the pressure of the cleaning fluid, means responsive to a rotative movement of said blower element for causing the cleaning fluid to exert a pressure on said valve opposed to and substantially equal to the pressure tending to seat the valve, and means for retarding movement of the valve during the initial closing movement only thereof. 145
16. In a fluid heater cleaner, a rotatable blower element, means for rotating said blower element, a valve for controlling the admission of cleaning fluid to the blower element, means actuated by the pressure of the cleaning fluid for actuating said valve, and means actuated by said blower element to cause said last men- 150

tioned means to open said valve and hold the same open during a predetermined portion only of the rotation of the blower element.

17. In a fluid heater cleaner, the combination of a movable blower element, a fluid passage for supplying cleaning fluid to said blower element, a valve controlling the flow of cleaning fluid through said fluid passage, a piston connected to the low pressure side of said valve, an auxiliary valve controlling the flow of cleaning fluid through said valve to act on said piston to cause the latter to open said valve, and a single means for effecting an actuation of said auxiliary valve and a movement of said blower element.

18. In a boiler cleaner having a blower element and a valve controlling the supply of

cleaning fluid to said element, means for oscillating said blower element within predetermined limits, and means responsive to an initial rotative movement of said element from one of said limits toward the other for causing the pressure of the cleaning fluid to exert a force which unseats said valve.

19. In a boiler cleaner, the combination with an oscillatory blower element and a valve controlling the delivery of a cleaning fluid to said element, of means responsive to a movement of the blower element for causing the cleaning fluid to move said valve to open position, and means for regulably retarding seating of said valve.
